Primary Examiner — Michael A. Pratt*Assistant Examiner* — Adam C Mager(57) **CLAIM**

The ornamental design for a product display structure, as shown and described.

DESCRIPTION

FIG. 1 is a front view of a product display structure, showing my new design.

FIG. 2 is a rear view thereof.

FIG. 3 is a left view thereof.

FIG. 4 is a right view thereof.

FIG. 5 is a top view thereof.

FIG. 6 is a bottom view thereof.

FIG. 7 is a top-front-left perspective view thereof.

FIG. 8 is a bottom-rear-right perspective view thereof.

FIG. 9 is a bottom-front-right perspective view thereof; and,

FIG. 10 is a top-rear-right perspective view thereof.

The shade lines show surface contour and not surface ornamentation.

In FIGS. 7-10, the broken line showings of products being present within the product display structure illustrate environmental items, and the broken lines form no part of the claimed design.
